UNITED STATES PATENT OFFICE.

LEO J. HUSS, OF SHAKOPEE, MINNESOTA.

PUMP JACK.

Application filed March 14, 1924. Serial No. 699,232.

To all whom it may concern:

Be it known that I, LEO J. HUSS, a citizen of the United States, residing at Shakopee, in the county of Scott and State of Minnesota, have invented certain new and useful Improvements in Pump Jacks; and I do hereby declare the following to be a full, clear, and exact description of the invention, such as will enable others skilled in the art 10 to which it appertains to make and use the same.

My invention relates to a power transmission device or mechanism generally known to the trade as a "pump jack," and 15 which mechanism transforms the rotary motion of an engine-driven shaft to a reciprocating motion applied to the pump. Among other things, the invention involves a rocking beam or intermediately pivoted 20 lever slotted at one end, and a pair of laterally spaced gears rigidly connected for common rotation by a wrist pin that works in the slot of said lever. The lever works between the gears and the gears are given 25 simultaneous rotation by a pair of pinions or a wide-faced pinion carried by a shaft to which the power is applied, preferably by a pulley directly secured to said shaft. These features and others will be more fully 30 described in connection with the accompanying drawings, which illustrate the invention and wherein like characters indicate like parts throughout the several views.

Referring to the drawings:

35 Fig. 1 is a side elevation showing the complete pump jack;

Fig. 2 is a transverse vertical section taken on the line 2—2 of Fig. 1;

40 Fig. 3 is a front elevation of the pump jack;

Fig. 4 is a plan view of the pump jack with the upper portion or hood-like cover of the case removed; and

45 Fig. 5 is a section taken through the complete pump jack approximately on the line 5—5 of Fig. 4.

The numeral 6 indicates a box-like oil-containing case, preferably of rectangular form. The numerals 7 and 8 indicate rectangular marginal supplemental box sections of approximately the same horizontal form as the box 6, provided with supplemental shaft bearings 9, 10 and 11, and connecting flanges 12, which latter are preferably connected by short nut-equipped bolts 13. The lower supplemental frame section

7, at longitudinal sides, has depending flanges 14 that fit groove-like seats 15 formed in the upper portion of the box 6 near its sides. Long nut-equipped bolts 16 60 are passed through perforations in the flanges 12 and through anchoring lugs 17 shown as cast integral with and projected outward from the lower side portions of the box or case 6. The outer ends of the 65 shaft bearings made up of the supplemental bearings 9—9 and 10—10 are closed, and the outer end of one of the bearings 11 is also closed, while the other bearing 11 is open, so that a shaft, presently to be noted, may 70 extend therethrough. The upper supplemental box section 8 is shown as provided with a projecting rim flange, which, by short nut-equipped bolts 18, is detachably secured to the correspondingly formed 75 flange of a hood-like cover 19.

Mounted in the bearings 10 is a rock shaft 20 and mounted in the bearings 11 is a power-transmitting shaft 21. Working within the case is a pair of laterally spaced 80 spur gears 22 of the same diameter and same number of teeth, and these gears are provided with outwardly projecting trunnions or short shafts 23 that are journaled in the bearings 10. The shaft 21 is provided with spur pinions 24 that mesh with the gears 22 and impart simultaneous and like rotary motion thereto. The two gears 22 are connected by a wrist pin 25 that works in a long slot 26 of an oscillatory 90 lever or walking beam 27 having a hub 28 pivotally mounted on the rock shaft 20. The lever 27 projects through a slot 29 in the supplemental frame sections 7 and 8 and, as shown in Fig. 1, is pivotally connected to a link or rod 30, which, in turn, will be connected to the pump rod 30'. The numeral 31 indicates a pulley secured to that end of the shaft 21 that projects through the open end of the bearing 11. 100

It will be noted that the gears 22 are arranged to run in oil y contained in the box or main case section 6, so that all of the parts will be kept well lubricated by splashing and dropping of the oil. The 105 duplex arrangement of gears and pinions supports the wrist pin 25 at both ends and relieves the same from torque strains tending to tilt the same and to put the bearings of the gears under undue strain, such as 110 would be produced by force applied to a wrist pin carried by one such gear. Also,

the slotted end of the motion-transforming lever or walking beam is carried between the gears, where it will not only be kept well lubricated but will be carried into and out 5 of the oil.

The several parts that make up the casing are adapted to be independently cast and quickly assembled. When the bolts 16 are removed, leaving the bolts 13 applied, the 10 supplemental case sections 7 and 8 and also the cover 19, if desired, together with the working parts of the jack or power-transmitting device, may be removed from the main case or box without disturbing any of 15 the adjustments of the said running parts and, of course, they may be reapplied by reverse operation.

What I claim is:

1. A pump jack comprising a box-like 20 main case section, a supplemental case section detachably seated on said main case section, a pair of laterally spaced spur gears journaled to said supplemental case

section, a wrist pin rigidly connecting said two gears, a lever intermediately pivoted to 25 said supplemental case section and having a slotted end working between said gears and through the slot of which said wrist pin is arranged to work, and a driving shaft equipped with pinions meshing with 30 said two gears, said lever, gears, pinions and their shafts being removable from said main case section with said supplemental case section.

2. The structure defined in claim 1 in 35 which said supplemental case section is made up of two parts connected by a horizontal joint that splits the bearings that support said lever, gears and pinion-equipped shaft, the parts of said supplemental section being detachably connected by means independent of the means that connects the composite supplemental case section to the main case section.

In testimony whereof I affix my signature.
LEO J. HUSS.
